UNITED STATES PATENT OFFICE.

WILLIAM F. MURTHA, OF WATERBURY, CONNECTICUT, ASSIGNOR TO WATERBURY BUCKLE CO., OF WATERBURY, CONNECTICUT, A CORPORATION.

BUCKLE.

Application filed November 5, 1923. Serial No. 672,719.

To all whom it may concern:

Be it known that I, WILLIAM F. MURTHA, a citizen of the United States, residing at Waterbury, in the county of New Haven and State of Connecticut, have invented a new and useful Improvement in Buckles; and I do hereby declare the following, when taken in connection with the accompanying drawings and the characters of reference 10 marked thereon, to be a full, clear, and exact description of the same, and which said drawings constitute part of this application, and represent in—

Fig. 1 a view in front elevation of a rustless buckle constructed in accordance with my invention, shown as applied to a piece of webbing, which is partly broken away.

Fig. 2 an edge view thereof.

Fig. 3 a sectional view on the line 3—3 20 of Fig. 1.

Fig. 4 a view of the buckle-frame in front elevation on an enlarged scale.

Fig. 5 a plan view thereof, prior to the closing of the web-gripping members of the 25 frame, which are shown in their gripping positions by dotted lines.

My invention relates to an improvement in rustless buckles of the type shown and described in United States Patent No. 30 847,811, granted March 19, 1907, on the application of Morris Peller, the object of my present invention being to produce a wire-frame buckle in which the wire of the frame is bent to grip the fixed end of the webbing, 35 whereby an economy of time, labor and webbing is effected, all sewing of the webbing being eliminated.

With these ends in view, my invention consists in a wire-frame rustless buckle having 40 certain details of construction as will be hereinafter described and pointed out in the claim.

In carrying out my invention, as herein shown, the buckle-frame consists of a single 45 piece of wire bent to form a continuous straight lower bar 6, the ends of which are bent forward, then inward in front of the said bar, then upward and then outward to the ends of the said bar, to form two 50 complementary gripping-loops 7, located in the vertical plane in front of the lower bar 6 and extending toward each other. The upper reaches of these loops 7 are bent inward and then upward at a right angle to 55 produce the side bars 8 of the frame. The

respective ends of the wire are bent toward each other from the upper ends of the said side bars and at a right angle thereto to form aligned pintles 9, constituting in effect the upper bar of the frame and 60 providing for the pivotal mounting of an ordinary sheet-metal buckle-lever having a finger-piece 10 and gripping-edge 11 and hinges 12, which clasp the pintles 9. As thus shaped, the one-piece wire buckle-frame has a webbing-opening 13 in front of which the finger-piece 10 of the buckle-lever 65 normally depends.

In webbing my improved buckle, what is to be the fixed end 14 of the webbing 15 is 70 inserted into a narrow space formed between the front face of the lower bar and the inner faces of the vertically-arranged gripping-loops 7, which at this time stand away from the said bar, as shown in Fig. 75 5. When, however, the end 14 of the webbing is thus positioned, the loops are clamped down upon it into the positions shown by broken lines in Fig. 5, whereby the said end of the webbing is gripped between the loops and the lower bar and thus 80 permanently attached to the buckle-frame with the utmost economy of webbing and with the elimination of stitching. The webbing is now passed from front to rear, over the top of the lower bar 6, whereby the bend 16 is formed in it, then downward to form the usual loop 17 and then upwardly over the gripping-loops 7, and then from front to rear over the bend 16 of the webbing and 90 under the gripping-edge 11 of the buckle-lever and upward, as shown in Figs. 2 and 3.

I claim:

In a buckle, the combination with a one-piece wire frame bent to form a continuous straight lower bar, the ends of which are bent forward, then inward toward each other, in front of the said lower bar, then upward and then outward to the ends of the said bar to form two complementary web-gripping loops located in the vertical plane in front of the said bar, and the outer ends of the upper reaches of the said loops being bent rearward and then upward to 95 form the side-bars of the frame, and the upper ends of the said side-bars being bent inward toward each other to form pintle-ends constituting in effect the upper bar of the frame; of a buckle-lever mounted upon 100 105 110

the said pintle-ends of the frame, and a length of webbing having its fixed end gripped between the front face of the lower bar of the frame and the rear faces of

5 the vertically-arranged web-gripping loops standing in front of the said lower bar of the frame.

In testimony whereof, I have signed this specification in the presence of two subscribing witnesses.

WILLIAM F. MURTHA.
